UNITED STATES PATENT OFFICE.

NEIL SINCLAIR, OF OAKLAND, CALIFORNIA.

CLOSET-BED.

1,303,509.

Specification of Letters Patent. Patented May 13, 1919.

Application filed May 8, 1918. Serial No. 233,338.

To all whom it may concern:

Be it known that I, NEIL SINCLAIR, a citizen of the United States, residing at Oakland, in the county of Alameda and State of California, have invented new and useful Improvements in Closet-Beds, of which the following is a specification.

The present invention relates to improvements in that class of disappearing beds which, when not in use, are concealed within a closet or other receptacle, and when in use are moved outside of the closet into an adjacent room.

One object of the invention is to provide, in such a bed, means whereby the depth of the closet necessary to so conceal the bed may be the least possible.

A further object is to provide means whereby the bed may be swung from its position of concealment into its position of use and conversely with the smallest amount of effort.

A further object is to provide means for so supporting a bed which will be comparatively inexpensive.

A further object is to provide means for firmly supporting a foot piece in either a vertical position of use, or a horizontal position over the bed.

A further object is to provide improved means for holding the bed clothes, especially when the bed frame is in a vertical position.

In the accompanying drawing, Figure 1 is a perspective view of a closet and a bed in the position in which it is partly moved out for use; Fig. 2 is a horizontal section of the same showing the bed head in its innermost or concealed position, the remainder of the bed being omitted for clearness of illustration; Fig. 3 is a view similar to Fig. 2, showing the bed head in its extended position; Fig. 4 is a perspective view of an angle bar; Fig. 5 is a similar view of a clamp; Fig. 6 is an enlarged top plan view of a bottom arm or a bottom plan view of a top arm, and the supports therefor in one position of the door; Figs. 7 and 8 are views similar to Fig. 6, the door being in other positions; Fig. 9 is a detail side view of said bottom arm and parts adjacent thereto.

Referring to the drawing, 1 indicates a closet frame and 2, 3, swinging doors for closing said closet. To the door 3 close to its free edge is secured a hinge member 4, and in the knuckle 5 of said hinge member, which extends beyond said free edge, is

received a lower vertical member 6 of an angle bar 7, a horizontal member of which is extended and reduced in diameter, as shown at 8, and carries a nut 9 on its outer end which is threaded. Said reduced portion 8 extends through a horizontally directed hole 11 in the top transverse member 15 of a bed head 12, which carries the bed frame 10. Said bed head is supported at 60 the top by means of a clamp 13, which is in two halves, having curved portions 14 fitting snugly against said member 15 of the bed head, and curved portions 16 adapted to surround a vertically extending device, such as a round bar 17 and drawn together by 65 screws 18. Said bar 17 extends adjacent to said top member 15, and is also secured to the lowest member 19 of the bed head by a strap 21. Its lower end is retained by a 70 screw 23 in a socket 24 in the outer end of an arm 26, the inner end of which has a lug 27 slidable in a slot 58 in a plate 59 let into the floor of the room. Upstanding from a portion of said arm 26 offset from the lug 80 27 is a pin 61, which is pivoted to one end of a link 62 the other end of which link is pivoted on an unthreaded portion of a screw 63 screwed into the floor of the room adjacent to the closet.

The upper end of said bar 17 is connected, as shown at 28, to the outer end of a horizontal arm 29, the inner end of which is connected, as shown at 31, to the frame of the opening for the closet door not far from 90 its center in like manner as described for the pivotal connection of the lower arm 26 with the floor.

It will be seen from the above construction that so much of the weight of the bed is 95 supported by the bar 17 and not by the door that the strength of the hinges for the door and of the door itself need not be increased.

The bed being supposed to be in its concealed position with the lug or pivot 27 in 100 the innermost end of the slot 58, and it being desired to extend it for use, the door 2 is first swung wide open. The door 3 is then swung open sufficiently to permit the bed to clear the walls of the closet, and the bed is swung around the free edge of the door until it is again parallel with the door 3 but in the front instead of in the rear. The door 3 is then closed and the bed is lowered for use. In the horizontal movements of the door 3 and of the bed, the lug or pivot 27 travels in the slot 58 until, in 110

the final position of rest, it is in the front end of the slot.

It will be readily seen from a comparison of Figs. 2 and 3 which show respectively 5 the bed in the two positions, inside and outside the closet, that, if the lug 27 were stationary, it would have to be to one side (the left with the arrangement of the bed and arms shown) of the vertical plane extending 10 perpendicular to the front plane of the closet and through the knuckle or pivot 5. The location of the lug 27, if stationary, is very difficult to determine in actual practice, and the slightest deviation from its 15 correct position causes the moving parts to bind in passing from one position to another. It has been found practically impossible to install beds of this character with the accuracy necessary to prevent binding 20 if the bearing for the lug 27 is a stationary bearing let into the floor. But by providing a slot 58 in which the lug 27 can slide, no difficulty whatever is found in installing the bed.

25 I claim:

1. In combination with a door and a frame against which the door closes, an article of furniture, a vertically extending device attached thereto, a horizontally swinging arm carrying said device, and means for so pivotally connecting said article to the door adjacent to its free edge that said article can be swung bodily around the free edge of the door.

30 2. In combination with a door and a frame against which the door closes, an article of furniture, a vertically extending device attached thereto, a horizontally swinging arm carrying said device, a horizontally extending arm secured to said article, and a vertical pivot for said arm secured to a side of the door and located beyond its free edge.

35 3. In combination with a door and a frame against which the door closes, an article of furniture, a vertically extending device attached thereto, upper and lower arms swinging horizontally about ends thereof in vertical alinement, the other ends of the arms being connected to upper and lower por-

tions of said device, and means for so pivotally connecting said article to the door adjacent to its free edge that said article can be swung bodily around the free edge of the door.

4. In combination with a door and a frame 55 against which the door closes, an article of furniture, a vertically extending device attached thereto, upper and lower arms swinging horizontally about ends in vertical alinement, the other ends of the arms being connected to upper and lower portions of said device, a horizontally extending arm secured to said article, and a vertical pivot for said arm received to a side of the door and located beyond its free edge.

60 5. In combination with a door and a frame against which the door closes, an article of furniture, a vertically extending device attached thereto, upper and lower arms swinging horizontally about upper and lower ends 70 thereof in vertical alinement, the door frame and the floor being provided with horizontally extending slots in which said ends move, means for regulating the movement of said ends in said slots, the other ends of 75 the arms being connected to upper and lower portions of said device, and means for so pivotally connecting said article to the door adjacent to its free edge that said article can be swung bodily around the free edge of 80 the door.

65 6. In combination with a door and a frame against which the door closes, an article of furniture, a vertically extending device attached thereto, upper and lower arms swinging horizontally about upper and lower ends 85 thereof in vertical alinement, the door frame and the floor being provided with horizontally extending slots in which said ends move, means for regulating the movement 90 of said ends in said slots, the other ends of the arms being connected to upper and lower portions of said device, a horizontally extending arm secured to said article, and a vertical pivot for said arm secured to a side 95 of the door and located beyond its free edge.

NEIL SINCLAIR.
